UNITED STATES PATENT OFFICE.

MINER E. FENNER, OF SUMNER, NEBRASKA, ASSIGNOR OF ONE-HALF TO H. S. CLOUSE,
OF SUMNER, NEBRASKA.

HAYSTACKER.

Application filed August 13, 1925, Serial No. 49,951. Renewed December 23, 1926.

This invention relates to a hay stacker and has for its object, broadly, to provide a stacker consisting of few and simple parts so that it may be manufactured economically, and will be convenient in use. One of the specific objects is to provide a novel means which will operate automatically and effectively for unloading the fork. Another object is to provide means whereby a carrier-frame may be readily elevated or lowered by a single operator and may be maintained at a required degree of inclination. The invention also includes a carrier frame extension operating as a convenience when loading the fork.

With the foregoing objects in view and others to be mentioned hereinafter the invention presents a new and useful construction, combination and arrangement of parts as described herein and claimed, and as illustrated in the accompanying drawings, it being understood that changes in form, size, proportion of parts and minor details may be made as found to be of advantage, said changes being determined by the scope of the invention as claimed.

In the drawings, Fig. 1 is a plan view of the stacker. Fig. 2 is a side view of the same showing the fork in its lowermost position ready for loading. Fig. 3 is a plan view on an enlarged scale, being a detail relating to Fig. 1. Fig. 4 is a side view of the stacker showing the fork in an elevated position for unloading. Fig. 5 is a side view, being a detail relating to Fig. 2 or Fig. 4.

Referring now to the drawing for a more particular description, in which like characters indicate like parts in the several views, numeral 10 indicates a base frame of any suitable construction adapted to sustain the weight of a carrier frame 11, an adjusting-frame 12 and the load carried by a fork 13, said base frame consisting of a pair of parallel side plates 14 suitably connected by cross-plates 15 and 15', posts 16 preferably being secured to the side plates 14 at their rear ends and supported by braces 17.

Numerals 18 indicate the side plates for the carrier frame, preferably connected by cross-braces 19 and by a shaft 20. At 21 are indicated inclined extension-plates for the carrier-frame, these being suitably se-

cured to the inner sides, at the front ends, of the base-plates, and providing a pivotal mounting, indicated at 22, for the carrier-frame.

The adjusting-frame 12 consists of a pair of parallel links 23 connected and reinforced by suitable cross-bars 24, their upper ends being connected with the carrier-plates 18 by hinge-members 25, their lower ends being provided with wheels or rollers 26 which are disposed on the side-plates 14.

At *a* is indicated a shaft which is journaled in the posts 16 adapted to be rotated by a crank 27, and at 28 are indicated strands or cables which are connected with the lower end-portions of the links 23, and it will be understood that the carrier-frame may be elevated, as may be required, during the operation of building a stack, the lower ends of the links 23 being moved toward the posts 16, by rotating the shaft.

A second inclined extension is provided for the carrier-frame, this being at its distal end, and consisting of a pair of parallel extension-plates 29, their inclination being downwardly and rearwardly. The shaft 20 already mentioned, connects the ends of the plates 29, and at 30 are indicated a pair of stop-members or hooks which are disposed at the junction of the plates 18 and 29, and have an upward and forward curvature. Numerals 31 indicate brace-strips which connect the ends of the extension-plates 29 with the side-plates of the carrier-frame.

The fork 13 includes a pair of side-strips 32 adapted to be disposed at the inner sides of and to move between the carrier-plates 18 and between the extensions 21 and 29, said plates 32 being connected by suitable cross-strips 33 and 33', and being provided with suitable wheels or rollers 34 for engaging the plates 18 and 21, and each strip 32 is provided with a horizontally disposed pin or projection *b*.

Numerals 35 indicate comparatively short detent-members or hooks which are secured to the fork and which have a rearward curvature, and when hay, straw or similar material has been placed on the fork, these hooks tend to cause the load to remain thereon while moving upwardly on the carrier.

Numerals 36 indicate a pair of control-

bars for automatically changing the inclination of the fork to effect unloading, said bars being pivotally mounted at 37 upon the brace-strips 31, the outer ends of said bars 5 being provided with detents or fingers 38 for engaging the projections *b* of the fork.

Sheaves or pulleys 39 and 40 are provided, respectively, for the shaft 20 of the carrier-frame extension and cross-plate 15' of 10 the base-frame, and the fork may be moved by use of a strand or cable 41 which engages said pulleys, one of its ends being secured to the fork, and preferably to the cross-strip 33 of said fork, and any suitable power may 15 be applied to the cable 41 for moving the load. Numerals 42 indicate a pair of guard-strips which are mounted on the outer sides of the carrier-plates 18 to provide slots 43 for receiving the control-bars 36.

20 Having described parts and their uses, operation will be readily understood. The fork is loaded while in the position shown in Figs. 1 and 2 of the drawings, and by use of the cable 41 may be drawn upwardly to be 25 unloaded. When the fork approaches the top of the carrier-frame the projections *b* will engage the ends of the control-bars, and said bars together with the fork will have a swinging movement, said fork moving approximately into line with the inclined terminal extension 29 for releasing the load, the front wheels 34 of the fork engaging the stop-members or hooks 30. After the fork is unloaded it may move downwardly on 30 the carrier-frame to the position shown in Figs. 1 and 2 of the drawings, by action of gravity.

It will be appreciated that, on account of the provision of the extension 21, the fork 40 may be disposed in, approximately, a horizontal position for loading; the carrier-frame may be elevated conveniently from time to time, while building the stack; also the sudden termination of a forward movement of the fork coincident with its rocking movement when the wheels engage the hooks 30 tends to facilitate unloading and for removal of all parts of the load from the fork to advantage.

50 I claim as my invention,—

1. In a stacker, a carrier frame including a pair of connected, parallel, inclined side-plates each having a downwardly inclined, terminal extension, a fork movable on the carrier-frame, and a pair of pivotally mounted control-bars arranged to be moved by the fork for disposing it approximately in line with the downwardly inclined terminal extensions of the side-plates in engagement with said stop-members.

55 2. In a stacker, a carrier frame including a pair of connected side-plates each having a downwardly inclined, terminal extension and a stop-member, a pair of pivotally

65 mounted control-bars normally disposed approximately parallel with the side-plates of the carrier-frame, and a fork provided with projections and movable on the side-plates of the carrier-frame, its projections engaging the control-bars for disposing said fork 70 approximately in line with the inclined terminal extensions of the side-plates in engaged relation with the stop-members.

3. In a stacker, a carrier-frame including a pair of connected, inclined side-plates each 75 having a downwardly inclined, terminal extension and a stop-member, a pair of pivotally mounted control-bars normally disposed at the sides of the side-plates, and a fork provided with projections and having side-members normally disposed between the side-plates and being movable on the carrier frame, its projections engaging and causing upward swinging movements of the control-bars for disposing the fork approximately in line with the inclined, terminal extensions of the side-plates in engagement with said stop-members.

80 4. In a stacker, a carrier frame including a pair of connected, parallel, inclined side-plates, each being provided with a stop-member and a downwardly inclined terminal extension, a pair of pivotally mounted control-bars, a fork having a pair of side strips adapted to be disposed at the inner 85 sides of the side-plates of the carrier-frame and being movable on said carrier-frame into engagement with the control-bars and stop-members for causing a swinging movement of said fork, parts of its side-strips 90 moving between the downwardly inclined terminal extensions of said side plates.

95 5. In a stacker, a base-frame including a pair of connected side-plates, a pair of inclined extension-plates each being disposed 100 at the front end and secured to a side-plate of the base-frame, a carrier-frame including a pair of connected side-plates each being provided with a stop-member and having a downwardly inclined extension at its rear 105 end and pivotally connected at its front end with an extension-plate of the base-frame, a fork movable on the carrier-frame, a pair of control-bars arranged to be moved by the fork to change the direction of movement 110 of said fork and to dispose it between the side-plates of the downwardly inclined extension of the carrier-frame, and an adjusting-frame on the base-frame for moving the carrier-frame.

115 6. In a stacker, a rectangular base having an extension inclined downwardly from one of its ends, a carrier-frame including a pair of connected, parallel, inclined side-plates provided with stop-members, each side-plate having a downwardly inclined terminal extension and connected with the inclined extension of the rectangular base,

means for moving the side-plates to selected degrees of inclination relative to the rectangular base, a fork provided with wheels and projections and adapted to be moved on the side-plates, and a pair of control-bars adapted to be engaged by the projections of said fork to cause engagement

thereof with said stop-members and to dispose it approximately parallel with the inclined terminal extensions of the side-plates 10 of said carrier-frame.

In testimony whereof, I have affixed my signature.

MINER E. FENNER.
